Lamb & Summers,

Steam-Boiler Water Fire Box.

No 8,910.

Patented Apr. 27, 1852.

UNITED STATES PATENT OFFICE.

ANDREW LAMB AND WILLIAM ALLTOFT SUMMERS, OF THE COUNTY OF HANTS, ENGLAND.

STUD-BRACE FOR FLUES OF SHEET WATER-SPACE BOILERS.

Specification forming part of Letters Patent No. 8,910, dated April 27, 1852.

To all whom it may concern:

Be it known that we, ANDREW LAMB and WILLIAM ALLTOFT SUMMERS, of the county of Hants, in the Kingdom of Great Britain, have invented certain new and useful Improvements in the Boilers of Steam-Engines; and we do hereby declare that the following is a full, clear, and exact description of the principle or character which distinguishes them from all other things before known and of the usual manner of making, modifying, and using the same, reference being had to the accompanying drawings, forming a part of the same.

Our invention relates to certain improvements, hereinafter described, in the manner of staying or bracing what is commonly termed the "Lamb and Summers" boiler, or "sheet water-space" boiler.

The general arrangement of this kind of boiler is shown in Figures 5, 6, and 7. In this kind of boiler the tubes or flues are made flat-sided, instead of circular, and stayed or braced in the fire-spaces, instead of water-spaces. The flues or tubes are made very narrow, in order that a larger amount of efficient heating-surface may be placed in a given space than is practicable with circular tubes or flues; also, readier access can be obtained to all those parts of the boiler liable to become chocked with soot or deposit.

The manner in which the flues may be made is shown in Figs. 1, 2, 3, and 4.

Our invention consists in the manner of staying or bracing the before-described flat-sided flues in the fire or heat spaces; and its peculiarity consists in using a stud-brace, as shown in Fig. 8. The manner of forming this stud-brace is as follow: A piece of iron of any section convenient and of the proper length, regulated by the width of the flue, is taken and a collar, A, formed on it, to abut against one side of the flue, which flue is pierced to receive the part of the stud B continued past the collar A, which part B, after being passed through the side of the flue, is riveted over, as shown at C. The other end of the stud B simply abuts against the other side of the flue, and is not fastened to it. The pressure being on the outside of the flues, the braces have only to act in preventing a collapse. The boiler

is to be provided with an atmospheric valve opening into its interior, to prevent any less pressure than the atmospheric pressure to exist there, which less pressure might cause an injurious strain on the flues.

We are aware that the flues may be braced in the usual manner of bracing flat surfaces in steam-boilers—viz., by screwing the ends of the brace through the sides of the flue, or by using a socket and bolt, which socket is a metal cylinder enveloping the bolt and having its ends abutting against the sides of the flue, the bolt being held by a head and nut, or by means of a flat plate of metal supported by lugs or projections fastened to the sides of the flue and extending throughout the length of the flue. To these methods our method is superior in the following respects: First, it requires less weight of materials, as our stud-brace is less in length than any of the others and of less section also, excepting, in this respect alone, the screw-brace; second, less labor in workmanship, having only one end fastened, instead of both ends, and also by having that end fastened on the sheet composing one side of the flue before the said sheet is made into the flue, as it is then more accessible to work at. The sheet composing the other side of the flue has only to be brought up against the studs, and the flue is complete.

The inferiority of the socket-and-bolt method consists in the greater amount of materials and labor required—viz., the enveloping-socket, the screw cut on the bolt, the head and nut of the bolt, and the greater length of bolt. The inferiority of the screw-brace method consists in the greater amount of materials and labor, greater liability to destruction, and less security. There is greater amount of materials, because a greater length of brace is required; greater amount of workmanship, because a screw has to be cut on the whole length of the bolt and in the sides of the flue, and the holes in the sides of the flue have to be made carefully opposite each other and at right angles to the sides of the flues. There is more liability to destruction, because the water will percolate in between the threads of the screw and destroy them by corrosion; less security, because there are only the screw-threads in a thin piece of metal, the sides of

the flue never exceeding one-fourth inch in thickness to sustain the entire pressure. The plate-bracing is inferior, because it does not conduct the heat to the water, and will rapidly warp and burn out by the heat. It is also of vastly greater weight and more cost.

What we claim as our invention, and desire to secure by Letters Patent, is—

The stud-brace for bracing the flat surfaces of steam-boilers, substantially as described in the foregoing.

In witness whereof we, the said ANDREW LAMB and WILLIAM ALTOFT SUMMERS, have hereunto set our hands this 6th day of June, in the year of our Lord 1849.

ANDW. LAMB.
W. A. SUMMERS.
